UNITED STATES PATENT OFFICE.

JOSEPH A. SOMERVILLE, OF ST. LOUIS, MISSOURI.

WIPER.

Application filed December 18, 1924. Serial No. 756,679.

To all whom it may concern:

Be it known that I, JOSEPH A. SOMERVILLE, a citizen of the United States, residing at the city of St. Louis, in the State of Missouri, have invented certain new and useful Improvements in Wipers, of which the following is a specification.

This invention relates to wipers, and more particularly to power driven wipers for the window panes of street cars and the like, whereby the outer side of the pane, which is ordinarily inconveniently accessible for cleaning from the inside of the car, may be readily cleaned at desired intervals by mere momentary pressure on a manually operated switch arranged within convenient reach of the motorman.

The advantages above set forth and others incident to the invention will be best understood and appreciated from the following description of the preferred form of this invention, selected from divers embodiments for the purpose of illustration.

In the accompanying drawings forming part of this specification, in which like numbers of reference denote like parts wherever they occur,

Figure 1 is a fragmentary elevation of the outside of a car vestibule, showing the wiper of this invention applied to the window thereof;

Figure 2 is a sectional view, taken on the line 2—2 in Figure 1;

Figure 3 is a transverse sectional view through the wiper proper, taken on the line 3—3 in Figure 1;

Figure 4 is a detail sectional view of the operating switch, taken on the line 4—4 in Figure 1; and

Figure 5 is a transverse sectional view through the solenoid and guide casing therefor, taken on the line 5—5 in Figure 1.

A window sash 1, including window pane 2, is slidable, for the purpose of opening or closing the window, in the usual manner in the vestibule frame 3. On the outer side 4 of the frame 3 are mounted at either side of the window pane 2, the guides 5, formed of non-magnetic material, and preferably extending from the roof to the floor of the car. The guides 5 are preferably tubular in form, and preferably have integral therewith or affixed thereto in any suitable manner the flanges 6, whereby the tubes 5 may be attached to the frame 3 by screws or other suitable fastening means 7.

Solenoids 8 and 9 are secured in the upper ends of their respective tubes 5 preferably by screws 10, and solenoids 11 and 12 are likewise secured in the lower ends of their respective tubes. Plungers 13 are common to the upper and lower solenoids of each guide 5, and have affixed thereto intermediate their ends the collars or slides 14, which latter are preferably retained in position on the plungers 13 by the screw studs 15, screw-threading laterally into the slides 14 and seating against the the plungers 13. Tubes 5 are slotted at 16 between the upper and lower magnets to permit the passage of the studs 15, which extend from the ends of the wiper holder 17. Wiper holder 17 is preferably tubular in form, and slotted at 18 on the side thereof facing the pane 2. The tube 17 is normally under an elastic strain which tends to close the slit 18, and by reason thereof securely holds wiping strip 19 in the said slit. Wiping strip 19 may be of any suitable material, but rubber is deemed preferable. The ends of tube 17 embrace the studs 15, and are secured thereto preferably by transverse bolts 20.

A switch 21, comprising button or plunger 22, casing 23, blade 24, and contacts 25 and 26 is inserted in the inner side of the frame 3 at a point within convenient reach of the motorman, preferably adjacent the pane at a point intermediate the vertical dimension thereof. Wires 27 and 28 are connected to the source of electric current, wire 27 leading 90 to resilient blade 24, which normally impinges against stop or contact 25, from whence the current is conducted through wire 29 to solenoid 9, from thence by wire 30 to solenoid 8, and from thence by wire 31 95 back to wire 28. Contact 26, wire 32, solenoid 12, wire 33, solenoid 11, and wire 34 constitute the alternative circuit through which the current passes when plungers or button 22 is depressed.

With current supplied through wires 27 and 28, the wiper is normally held in the elevated position shown in Figure 1, the plungers 13 being drawn up into their respective upper solenoids 8 and 9. Should the vision of the motorman become obscured by the accumulation of moisture and other deposits on the outside of the pane 2, the window may be readily cleaned with a minimum of effort by merely pressing the button 110 22, whereby blade 24 is depressed from its normal position and into contact with stud

26, de-energizing the upper solenoids 8 and 9, and supplying the current to the lower pair of solenoids 11 and 12 instead, whereby
 5 plungers 13 are then attracted by and descend into the lower solenoids 11 and 12 carrying with them wiper 17. When button 22 is released, blade 24 springs back to its normal position, discharging lower solenoids 11 and 12 and recharging upper solenoids 8
 10 and 9, causing wiper 17 to ascend to its normal elevated initial position. Thus every time the switch is operated, wiper 17 completes one complete descending stroke and one complete ascending stroke. The lower
 15 magnets 11 and 12 may be designed with fewer ampere-turns than the upper magnets 8 and 9, since the weight of the wiper and associated plungers is favorable to the descent of the wiper.

20 I claim:

1. In a window wiper, a pair of laterally spaced guide tubes respectively slotted for a portion of their length to provide guide openings, a plunger within each guide tube
 25 adapted to slide from one end to the other thereof, a slidable collar on each plunger, a

pair of studs, each of said studs having a screw-threaded shank engaged in a screw-threaded opening in a collar and seating 30 against the plunger for locking the said collar thereon, a wiping strip, a holder therefor having its opposite ends embracing the said studs, and removable transverse bolts 35 securing the said ends of the holder to the said studs.

2. In a window wiper, a pair of spaced guides, slides constrained to move within the said guides, a wiping strip, a spring-metal tube slotted on one side to accommodate the 40 said wiping strip and normally under an elastic strain to close the slotted side upon the strip, a connecting stud between each slide and the adjacent end of the tube, each of the said studs having one of its ends in screw-threaded engagement with the slide 45 and the other end embraced by the tube, and means for releasably locking the said embraced ends of the said studs to the said tube.

In testimony whereof I hereunto affix my signature.

JOSEPH A. SOMERVILLE.
